UNITED STATES PATENT OFFICE.

ALBERT BABENDREER AND CLIFFORD R. WASSELL, OF OCEAN SPRINGS, MISSISSIPPI.

ANTIFREEZING DEVICE.

1,091,472.

Specification of Letters Patent. Patented Mar. 31, 1914.

Application filed June 5, 1912. Serial No. 701,761.

To all whom it may concern:

Be it known that we, ALBERT BABENDREER and CLIFFORD R. WASSELL, residing at Ocean Springs, in the county of Jackson and State 5 of Mississippi, and both citizens of the United States, have invented or discovered certain new and useful Improvements in Antifreezing Devices, of which improvements the following is a specification.

10 Our invention relates to devices used in connection with water-pipe systems to prevent the freezing of water carried in the pipes. The essential features of such a device are a shut-off valve and means for operating such a valve whenever the water in 15 the piping system is liable to freeze.

It is well known that, at water-freezing temperature, water in a piping system is less liable to freeze when flowing through the 20 pipe than when it is lying quietly therein. Such being the case it is desirable to regulate the operation of anti-freezing shut-off valves so that, when water is flowing through the pipes, a lower surrounding temperature will be required to make effective 25 the valve-operating means than when the water is not flowing through the pipes.

The object of our invention is to provide 30 an anti-freezing device, which is of simple and inexpensive construction and which will be efficient in its operation.

A further object of our invention is to provide such a device, which will operate at different surrounding temperatures, such 35 temperatures depending upon the condition of the water within the pipes as to whether or not it is flowing, and further depending upon the rate of flow of water in the pipes.

The preferred embodiment of our invention 40 is illustrated in the accompanying drawing, which forms part of our specification.

In this drawing Figure 1 is an elevation 45 of our preferred form of shut-off mechanism; Fig. 2 is an enlarged sectional view of a portion of the mechanism shown in Fig. 1; Fig. 3 is an elevation, partly in section, of an alternative form of valve construction; Fig. 4 is a sectional elevation of 50 an alternate form of valve operating means; and Fig. 5 is a sectional plan view taken on the line V—V, Fig. 4.

In the several figures like numerals are used to designate like parts.

55 Having reference, first, to the means for

operating the shut-off valve, our preferred operating means consists of a chamber, adapted to contain a suitable quantity of water and oil, or, in place of oil, any suitable liquid that will not mix with water and which freezes at a substantially lower temperature than water. Such a chamber 1 is 60 particularly illustrated in Fig. 2, and, as shown, is preferably constructed in such a manner that one wall of the chamber is 65 formed by the pipe section 2. The chamber 1 may be filled with water and oil; and a tube 3 may extend from the oil-containing portion of the said chamber to a suitable pressure-operated valve, to the end that, 70 when the water within the said chamber freezes, a portion of the oil will be expelled from the chamber and made effective to operate such valve.

The chamber 1 will, of course, be placed 75 at the most exposed portion of the piping system 4, and in such position its outer wall will be exposed to the temperature conditions of the atmosphere, while its inner wall will be exposed to the temperature conditions of the water flowing through the pipe section 2. It will therefore readily be seen that, when the water in the pipe system 4 is not flowing, the water in the chamber 1 will, when the outer wall thereof is exposed 80 to a freezing temperature, freeze at a relatively higher temperature than when water is flowing through the pipes 4 and applying heat to the said chamber through the inner wall thereof. Also the quantity of heat 85 passing from water in the pipes 4 to the water in the chamber 1 will be dependent upon the rate of flow of the water through such pipes, and the temperature of such water.

Our preferred form of shut-off valve is 95 particularly illustrated in Fig. 2. The tube 3, leading from chamber 1, is connected to a cylinder 5 in which a reciprocating plunger valve may be operatively disposed. Such 100 valve may consist of a piston or plunger 6 and a valve 7; and the valve is preferably arranged to close against the direction of flow through the pipes 4.

To the end that the pipes beyond the 105 shut-off valve may be properly drained, we provide a drain valve, adapted to be opened by the seating of the main shut-off valve. Such a drain valve 8 may be held yieldingly in closed position by a spring 9, and may be 11

provided with a slotted stem 10, the lower end of which may be engaged by a finger 11 secured to the plunger 6. The drain valve 8 may be arranged to operate subsequently to the closing of the shut-off valve by interposing a spring 12 between the finger 11 and the valve 7.

In order to admit air to the piping system after the shut-off valve has been closed and the drain valve opened, a suitable check valve 14 may be placed at the highest point of the said system. Such a check valve may be constructed to be held in closed position by the pressure of the water within the pipes, and may open to let air into the piping system 4 when such pressure is relieved by the operation of the shut-off and drain valves.

A convenient means for thawing the ice in the chamber 1 may consist of a trough 20 adapted to receive hot water from a suitable pipe 21. The bottom of the said trough may be provided with a plurality of holes 22, through which the hot water may flow to the sides of the said chamber. Also the thawing of the ice in the said chamber may be effected by means of a suitable electrical resistance coil 23, surrounding the said chamber as shown in Fig. 2.

An alternate form of shut-off valve is illustrated in Fig. 3. In this construction the plunger 6^a has link connection to the arm 15 of an ordinary water pipe valve 16. The fluid, entering the cylinder 5^a from the tube 3^a, will be effective to move the plunger 6^a downwardly and thereby close the valve 16; and the water from the pipes above the said valve will flow through the drain-cock 17. In order to open the valve 16 after the ice in the chamber has been thawed, a suitable spring 19 may be mounted, as shown, within the chamber 5^a.

In Figs. 4 and 5 we have also shown an alternate form of liquid-containing chamber consisting of a U-shaped yoke 18 adapted to fit tightly around the pipe 4^a. Such a chamber, together with the valve construction shown in Fig. 3, may be used in connection with a previously installed water-pipe system without cutting into the pipes.

The operation of our anti-freezing device, and particularly that form illustrated in Figs. 1 and 2, is as follows: A suitable quantity of water is placed in the chamber 1 and the rest of the said chamber, as well as the tube 3 and a portion of the chamber 5, is filled with oil. As long as the water in the chamber 1 does not freeze, the pressure of the water in the pipes 4 will be effective to keep the valve seat 7 raised and the check 14 closed. When the water in the chamber 1 freezes it expands about one ninth of its volume and forces a corresponding volume of oil from the chamber 1 to the cylinder 5, wherein it becomes effective to

force the plunger 6 from said cylinder and hence close the valve seat 7. The further movement of the plunger 6 will be effective to compress the spring 12 so that the finger 11 will engage the lower extremity of the slot 10 and open the valve 8 against the tension of the spring 9. After the flow of the water has been shut off by the valve seat 7, and the valve 8 opened, the check valve 14 will open to permit air to enter the pipes 4 so that the water contained therein may drain from the valve 8.

The water supply may be restored by causing hot water to flow through the pipe 21 into the trough 20 and down the sides 80 of the chamber wall until the ice therein has been melted, or by supplying electrical current to the resistance coil 23. The pressure of the water against the valve seat 7 will then open the shut-off valve and cause 85 the volume of oil previously expelled from the chamber 1 to return thereto.

While we have illustrated but one freezing chamber in the piping system, it will be apparent that under some conditions of 90 service a plurality of such chambers at different portions of the piping system may be desirable.

We claim as our invention:

1. As a means for operating a valve controlling the flow of water through a pipe to prevent its freezing therein, a rigid chamber filled partly with water and partly with a liquid freezable at a temperature lower than water, said liquid having further a 100 different specific gravity than water and not soluble therein, the water in said chamber being exposed simultaneously to the temperature of water in a pipe and to that of the surrounding atmosphere. 105

2. The combination with a water pipe, and a valve for controlling the flow of water therethrough, of a valve-operating means consisting of a single rigid chamber filled partly with water and partly with a liquid in bodily contact with the water and freezable at a temperature lower than water, said liquid having a different specific gravity than water and not soluble therein, the water in said chamber being exposed simultaneously to the temperature of the water in said pipe and to that of the surrounding atmosphere and operative connection between said chamber and said valve, whereby the liquid in said chamber becomes effective to operate said valve on and by the freezing of the water in said chamber. 110 115

3. The combination of a water pipe, and a pressure-operated valve controlling the flow of water therethrough, of a valve operating means consisting of a rigid chamber surrounding said pipe, said chamber being filled partly with water and partly with a fluid freezable at a temperature lower than water, said liquid further having a different 120 125 130

specific gravity than water and insoluble therein, a pipe also filled with said liquid and extending from that portion of said chamber in which said liquid is disposed to 5 said valve, the pressure imparted to said liquid by the freezing of the water in said chamber being effective to operate said valve.

4. The combination of a water pipe, a pressure-controlled valve in said pipe opening in the direction and by the pressure of 10 the flow of water therethrough, a rigid chamber surrounding said pipe and filled partly with water and partly with a liquid

freezable at a temperature lower than water, a pipe also filled with said liquid and extending from that portion of said chamber in which said liquid is disposed to said valve. 15

In testimony whereof we have hereunto set our hands.

ALBERT BABENDREER.
